UNITED STATES PATENT OFFICE.

PETER BUSHMAN, OF ALGIERS, LOUISIANA.

NON-REFILLABLE BOTTLE.

1,116,990.

Specification of Letters Patent.

Patented Nov. 10, 1914.

Application filed November 21, 1913. Serial No. 802,251.

To all whom it may concern:

Be it known that I, PETER BUSHMAN, a citizen of the United States, and a resident of Algiers, in the parish of Orleans and 5 State of Louisiana, have made certain new and useful Improvements in Non-Refillable Bottles, of which the following is a specification.

This invention relates to non-refillable 10 bottles and more particularly to a closure or stopper adapted, when used with an ordinary bottle to render the same non-refillable.

One of the principal objects of the invention is to provide a stopper or closure of 15 the class described, embodying means for allowing the exit of the contents of a bottle with which it is used, but for preventing the refilling of the bottle.

Another object of the invention is the 20 provision of a device of the class described, having a gravity valve and a manually actuatable valve adapted to coact in allowing the contents of a bottle to be poured out when the bottle is inverted, but to prevent refilling of the bottle when the same is in upright position, the gravity actuatable valve adapted to close automatically to prevent refilling, irrespective of the position of the manually actuatable valve.

30 A further object of the invention is the provision of a device of the class described which will be comparatively simple, durable, efficient in operation, and comparatively inexpensive to manufacture.

35 With these and other objects in view which will become apparent as the description proceeds, the invention resides in the construction, combination and arrangement of parts hereinafter more fully described 40 and claimed, and illustrated in the accompanying drawing, in which like characters of reference indicate like parts throughout the several figures, of which—

45 Figure 1 represents a vertical transverse sectional view taken through the device, showing the same in position in a bottle, the valves being shown in closed position. Fig. 2 represents a view similar to Fig. 1, the bottle being shown in inverted position, the 50 valves being open. Fig. 3 represents a vertical transverse sectional view of the upper end of the tube taken at right angles to Fig. 1. Figs. 4 and 5 represent horizontal sectional views on the lines 4—4 and 5—5 of Fig. 1, and Fig. 6 represents a horizontal 55 sectional view on the line 6—6 of Fig. 1.

Referring more particularly to the drawing, 5 indicates the neck of a bottle, having position therein the hollow tube 6, which extends substantially the length of the neck, 60 and which extends at its upper end above said neck, a hollow substantially conical cap 7 being secured by means of an annular ring 8 with which it is integrally formed, to the upper end of tube 6, the wall of the cap occurring in spaced relation to the tube, at the lower end thereof, for protecting the same, the upper end of the cap being reduced to merge with the tube 6 and form an extension thereof. The ring 8 forms a shoulder 65 70 for limiting the movement of tube 6 within the neck of the bottle. The cap 7 not only acts as a protection for the tube to permit insertion of instruments for opening the valves, but lends a more attractive and finished appearance to the device. Near the central portion of the tube, and near the lower end thereof, are situated a pair of annular valve seats 9 and 10 respectively, and a pair of ground valves 11 and 12 are seated 75 80 thereon and are adapted to open in the same direction. The lower valve 12 has formed thereon, a downwardly extending tubular stem 13 provided with a plurality of openings 14. Said valve is also provided with 85 an upwardly extending tubular valve stem 15 of smaller diameter than tube 6, said stem extending at its upper end through a perforate annular stem guide 16. A ball 17 is contained within the valve stem 15, and 90 normally holds valve 12 in closed position.

The upper valve 11 has formed thereon, a downwardly extending tubular stem 18 similar to valve stem 13. Resting on valve 11 is a disk 11^a having a pair of upwardly 95 extending arms 19 connected at their upper ends to a disk 20 of a diameter equal to the inside diameter of the tube, said disk 20 having formed integrally therewith, an inverted conical lug 21, said disk and lug 100 being provided with a plurality of perforations 22. The upper end of tube 6 is closed as at 23, by a perforated disk and through said disk extends a vertical pin 24 threaded at its lower end into disk 20, and secured at its upper end in a top valve 25, which is normally seated in the open end of the upper reduced portion of cap 7. A coiled spring 26 is interposed on pin 24 between disk 23 and disk 20, for normally holding 110 top valve 25 in closed position.

In order to manually operate valve 25,

there is provided a plunger rod 27 extending horizontally through the wall of cap 7, and of the upper end of tube 6, and provided with an enlargement 28 at its inner end having a beveled surface in contact with lug 21. The outer end of rod 27 is provided with a disk 29 for forming a thumb rest, and a coiled spring 30 is interposed upon the rod between tube 6 and a collar 31, secured on the rod, for normally holding said rod in an outer position.

In order to pour the contents from the bottle, the latter is inverted as shown in Fig. 2, and plunger rod 27 pressed inwardly, whereupon valve 25 is opened, and at the same time ball 17 rolls downwardly in the stem 15 into valve stem 18 and against the lower side of valve 11, opening the same, and by reason of the weight of liquid, and the force of gravity, valve 12 is moved downwardly and with it valve stems 15 and 13, the latter extending through valve seat 10 for guiding valve 12, the movement of said valve being limited by the contact of valve stem 15 with valve stem 18, while the movement of valve 11 is limited by contacting with disk 11^a. When the parts are in the position described, egress of the liquid may be had through valve seat 10, the openings 14 in stem 13, into tube 6, around stem 15, through the openings in stem guide 16, through the openings in valve stem 18, around ball 17, and out through the openings in disk 20 and closure 23, through the open end of cap 7. The flow of liquid may be instantly cut off by releasing plunger rod 27, whereupon valve 25 by action of spring 26 will assume its closed position. Although the valve 25 may be opened when the bottle is in upright position, the valves 11 and 12 will always be closed, when the bottle is in that position, so that refilling of the bottle is impossible, and the valve 11 will also close as the valve 25 is closed, when the bottle is in inverted position. When originally inserting tube 6 in the neck of a bottle, the tube may be cemented, or otherwise secured therein, so that it is impossible to remove the tube without breaking the bottle.

Although I have described the preferred embodiment of my invention, I may desire to make such changes in the construction, combination and arrangement of parts as do not depart from the spirit of the invention and the scope of the appended claims.

Having thus fully described my invention, what I claim as new and desire to secure by Letters Patent is:

60 1. A bottle having a hollow tube secured in the neck thereof, said tube extending above said neck, a hollow cap on the upper end of the tube in contact with the upper end of the bottle neck for limiting the movement of the tube therein, said cap hav-

ing a reduced portion in alignment with said tube, a valve seated in the reduced portion, a second valve seated in said tube, a perforated closure in the upper end of the tube, a stem slidably extending through the closure, and connected to first said valve, a cam surface connected with the stem, a plunger rod through said cap and tube, the inner end of said rod being enlarged and beveled to contact with said cam surface whereby when said rod is pushed inwardly, the first said valve is opened, means for normally holding said valve in closed position, means for holding said plunger rod in outward position, a gravity valve in the lower end of said tube, a heavy body normally carried by the gravity valve and adapted to open second said valve when the gravity valve is opened, and means on said stem to limit the movement of second said valve. 85

2. A bottle having a hollow tube secured in the neck thereof, said tube extending above said neck, a hollow cap secured to the upper end of said tube in contact with said bottle neck, said cap having a reduced portion aligning with said tube, a valve normally seated in said reduced portion, a second valve in said tube, means carried by first said valve whereby the movement of the second valve is limited, means for actuating first said valve, an annular valve seat in the lower end of said tube, a gravity valve normally seated thereon, a hollow valve stem extending from said lower valve downwardly through said valve seat, a hollow valve stem extending upwardly from said lower valve, a perforated disk through which said upwardly extended stem is guided, and a ball in said upwardly extending stem adapted to normally hold said lower valve in closed position, and to open said second valve when the lower valve is open. 95

3. A bottle having a hollow tube secured in the neck thereof, said tube extending above said neck, a hollow cap secured to the upper end of said tube and having a reduced portion aligning with said tube, a manually actuatable valve for closing the reduced portion and a valve for closing said tube near the upper end thereof, manually actuatable means for opening first said valve, and a gravity valve in the lower end of said tube actuatable independently of first said valve, said gravity valve adapted to open when said bottle is inverted, and means for opening second said valve when said gravity valve is opened. 110

4. A bottle having a hollow tube secured in the neck thereof and extending above said neck, a hollow cap secured to the upper end of said tube and having a reduced portion aligning with said tube, the walls of said cap occurring in spaced relation to said tube at the inner end of the cap, a plunger rod guided 125

in the walls of said tube and cap, a collar on said rod between said tube and cap, a spring on said rod between said tube and collar for normally holding said rod in an 5 outward position, a valve seated in said reduced cap portion, and coacting means between said plunger rod and said valve for lifting said valve when said rod is pushed inwardly.

10 5. A device of the class described comprising a tube, a cap with which the tube at one end is in communication, a manually operable valve for controlling the exit of fluid through the cap, gravity actuable 15 means for controlling the passage through the tube, a disk, means for supporting said disk on the manually operable valve, said disk being disposed within the tube and adapted to limit the movement of the gravity 20 actuable means.

6. A device of the class described comprising a tube, a hollow cap of greater diameter than the tube secured on one end thereof, said cap having a reduced portion 25 forming an extension of the tube, a manually actuable valve normally seated in the reduced cap portion, a stem connected with the manually actuable valve, a second valve in the tube, means carried by the stem to 30 limit the movement of the second valve, a plunger rod extending through said cap into said tube, co-acting means between the manually actuable valve and plunger for opening said manually actuable valve when 35 said plunger rod is moved in one direction, and means for normally holding said manually actuable and gravity actuable valves in closed position.

7. A device of the class described comprising a hollow tube having a hollow cap 40

on one end thereof, said cap having a reduced portion alining with the tube, a valve for controlling the passage through said cap, manually actuable means for opening said valve, said means including a cam 45 member carried by the valve and a plunger adapted to coact with the cam member and a gravity actuable valve for controlling the passage through said tube.

8. A device of the class described comprising a bottle closure having a passage therethrough, a manually actuable valve operating to control the exit through one end of the passage, a stem carried by the valve, a perforated disk through which said stem extends, a lug 55 on said stem having a cam surface, a plunger carried by said closure and having a cam surface adapted to co-act with the cam surface of said lug when the said plunger is moved in one direction for opening said 60 valve.

9. A device of the class described, comprising a bottle closure having a passage therethrough, a manually actuable valve operated to control one end of the passage, 65 gravity actuable means for controlling the opposite end of the passage, the last said means comprising a lower gravity valve having a hollow stem extending upwardly therefrom, and an upper gravity valve having a stem extending toward said hollow stem, and a ball carried by first said stem and adapted when the closure is inverted to drop into second said stem and against the upper valve for opening the latter. 70
